UNITED STATES PATENT OFFICE.

NICHOLAS KAUTH, OF LOS ANGELES, CALIFORNIA, ASSIGNOR TO A. J. BAYER COMPANY, A CORPORATION OF CALIFORNIA.

ADJUSTABLE GUIDE FOR SLIDING DOORS.

Application filed February 7, 1927. Serial No. 166,522.

This invention relates to shoes or guides for sliding doors, and has for its object to provide means whereby the movement of the door is directed over a given path, or the 5 stop position of the door is fixed at a given point, or both.

Figure 1 is a section from a steel door carrying this invention.

Figure 2 is a bottom plan view thereof 10 enlarged.

Figure 3 is a vertical section along the lines 3—3 of Figure 1.

Figure 4 shows a bracket carrying a shoe applied to a wooden door.

15 Referring to the drawings, 1 represents the base of a pressed steel door, while 1^a (in Figure 4) represents a bracket carrying this invention, and is shown attached to a wooden door.

20 In the door base 1, like in all steel doors, there is an angle iron 8, riveted or welded thereto. The supporting rods 4 have their ends in the angle iron 8, and abut against the inner surface of the frame 1 of the door,

25 thus being retained therein. The adjusting screw 5 is retained by the same means, but in the door frame 1 there is found at 9, a hole of smaller diameter than the head of the adjusting screw 5. The screw 5 has a slot 6 cut in its head, so that a screw-driver, or a 30 like instrument, can be inserted therein, to adjust the shoe.

The shoe 2, which is guided in the guide rail 7 at the bottom of the door opening, slides 35 snugly on the rods 4 and is threaded through the screw 5, so that by turning the screw, the shoe can be shifted in respect to the thickness. The position of the shoe as thus adjusted, determines the vertical plane of the door.

40 The guide or shoe 2 is preferably of elliptical form, so as to minimize the friction between the bearing surfaces on the guide rail 7, attached to the building or structure.

45 The elliptical form of shoe permits a relatively great angle between the plane of the door and axis of the guide rail, without binding between the two, while maintaining rel-

atively large bearing surfaces between the shoe and the guide rail.

It will be seen from the above that both 50 the supports 4 and the adjusting screw 5 are retained within the construction of the door frame and that convenient, neat and simple means have been provided for regulating the path of the door.

55 In Figure 4, I have shown this invention applied to a wooden door. The invention here is applied in the form of a bracket secured to the wooden door by the screws 10.

What I claim as new and useful and desire 60 to secure by Letters Patent is:—

1. A shoe for sliding doors carried by supports from the door and having independent means for adjusting the shoe laterally on said supports in a transverse plane and securing 65 it in its adjusted position.

2. A shoe for sliding doors supported at its ends from the door with independent means engaging the intermediate portion of the shoe for adjusting the lateral position of 70 the shoe on the door.

3. An elliptical shoe for sliding doors supported at each end from the door with independent means engaging the intermediate portion of the shoe for adjusting the lateral 75 position of the shoe on the supports.

4. In a door having a guide shoe thereon, the combination of a base and a reinforcing member carried therein, supports for the shoe penetrating said reinforcing member 80 with their ends abutting and concealed by said door base, with independent means accessible through said base for adjusting said shoe on its supports.

5. The combination of a door having a 85 guide shoe, means for supporting the shoe for adjustment transversely with reference to the door, and means independent of such supporting means for such transverse adjustment and locking the shoe in its adjusted 90 position.

In testimony whereof I hereunto affix my signature.

NICHOLAS KAUTH.
